UNITED STATES PATENT OFFICE.

PAUL S. GRIERSON, OF SOUTH ORANGE, NEW JERSEY, ASSIGNOR TO CHARLES CORY & SON, INC., OF NEW YORK, N. Y., A CORPORATION OF NEW YORK.

RADIO LOUD-SPEAKING RECEIVER.

Application filed September 6, 1922. Serial No. 586,456.

To all whom it may concern:

Be it known that I, PAUL S. GRIERSON, a citizen of the United States, and resident of South Orange, in the county of Essex and State of New Jersey, have invented certain new and useful Improvements in Radio Loud-Speaking Receivers, of which the following is a specification.

This invention relates to a telephone receiver, and more particularly to a loud speaking telephone receiver especially adapted for employment with radio receiving apparatus.

A prime desideratum of my present invention comprehends the provision of a telephone receiver, especially intended for radio receiving sets constructed and designed to produce clear and loud tones for the faithful and efficient reproduction of speech, the receiver being constructed so as to be adjustable in a simple manner by the user or operator in accordance with the varying needs of service.

In the reception of radio telephonic impulses and the conversion the same to audio impulses, the efficiency of the telephone receiver used is dependent upon a number of important factors. One of the more important considerations resides in the fact that a telephone receiver, where a maximum sound emitting efficiency is desired, must be adapted to a given receiving set and to the location of such set relatively to the radio sending station, by reason of the fact that the efficient operation of the receiver is dependent upon the strength of the impulse transmitted thereto. As is well known, the strength of the incoming radio impulses of a receiving set is contingent upon such factors as the power of the sending station, the distance between the receiving set and the sending station and the existence of absorbing bodies in the field between the same; and the strength of impulses transmitted to the telephone receiver is dependent upon the such strength of incoming impulses as well as upon the characteristics of the particular receiving set used, the received im-

pulses for energizing the magnet coils of the telephone receiver being therefore of different degrees of strength or weakness varying with the particular set and receiving station. To produce maximum sound effects under any and all of these varying conditions, the receiver should be adapted to such varying degrees of strength of impulses, and the provision of such a receiver which may be adjusted to fit the varying needs of service is a principal object of the present invention.

The principal objects of my present invention may be said to include the provision of a radio telephone receiver which is adaptable to a given receiving set under differing conditions of service for adjusting for a maximum sound efficiency with a given strength of received impulse; the provision of a radio telephone receiver of this nature in which the distance between the diaphragm and the electromagnet unit of the receiver is variably settable to provide for the desired adjustment; the further provision of a radio telephone receiver in which a sensitive adjustment may be made by the user or operator in a simple manner; the further provision of a radio telephone receiver in which discordant vibrations of the electromagnet unit is minimized so as to permit of obtaining pure and clear tones; the still further provision of a telephone receiver of the nature referred to in which the parts are constructed and relatively arranged to provide a stable unit having a low center of gravity and the further provision of a telephone receiver made of a few parts which are easily assembled and disassembled for purposes of inspection and repair, with the parts inter-related to provide a loud-speaking receiver of attractive appearance.

To the accomplishment of the foregoing and such other objects as may hereinafter appear, my invention consists in the elements and their relation one to the other, as hereinafter particularly described and sought to be defined in the claims, reference

being had to the accompanying drawing which shows a preferred embodiment of my invention, and in which:—

Fig. 1 is a side elevational view of my improved radio telephone receiver,

Fig. 2 is a cross-sectional view thereof with the horn cut away,

Fig. 3 is a view taken in cross-section on the line 3—3, Fig. 2,

Fig. 4 is a view taken in cross-section on the line 4—4, Fig. 3, and

Fig. 5 is a bottom plan view of parts of the receiver shown in a reduced scale.

Referring now more in detail to the drawings, the receiver comprises a supporting base B which may be made for example of wood, a casing C carried by and attached to the base B by any approved means such as the spaced screws 10 which secure a marginal flange portion 11 of the casing C to the base B, the said casing comprising a body portion 12 housing the diaphragm D and the electromagnetic unit E and a cover 13 removably attachable to the casing body 12, the said cover being provided with a central boss 14 for receiving the amplifying horn 15.

As heretofore referred to, a principal object of the invention comprehends the provision of an improved radio telephonic receiver which is adjustable for producing a maximum sound efficiency with a given strength of received impulse. To accomplish this end, my invention comprises the provision of a telephone receiver in which the diaphragm D and the electromagnetic unit E are movable relatively to each other to vary the distance between the same, the one being adjustably settable relatively to the other. For a given strength of current energizing the coils of the electromagnetic E, the diaphragm D has a critical position for maximum efficiency, and must be located a given distance from the coils for a given strength of energizing current, the diaphragm having different critical positions for different strengths of energizing currents. By the relative adjustment, therefore, of the diaphragm and the electromagnetic coils, and by the provision of means whereby the diaphragm and the electromagnetic may be set or held in any adjusted position one relatively to the other, the characteristics of the receiver may be varied to fit the particular service requirements.

In my preferred construction as exemplified in the drawings, the relative adjustment between the diaphragm D and the electromagnetic E is provided for by stationarily mounting the electromagnetic E in the casing C in a manner as will be detailed hereinafter, and by mounting the diaphragm D so as to be adjustably settable with respect to the electromagnetic E, the said diaphragm D being to this end carried

by and attached to the cover 13 as by means of clamping the same between the said cover and a clamping ring 16, the said clamping ring 16 being attached to the cover by means of the securing screws 17, the clamping ring being adjustably movable in the casing body 12, the clamping ring being to this end externally threaded as at 18 for engagement with the complementary threaded portion 19 of the casing body 12. With this construction the casing cover 13 and the diaphragm D carried thereby may be microscopically adjusted and the distance between the diaphragm D and electromagnet E varied in slight degrees for producing a sensitive adjustment.

For the purpose of holding or setting the diaphragm D in any adjusted position, I provide locking means in the form of a set screw 20 threaded through a tapped bore in the casing body 12 and engageable with a depending skirt or flange portion 21 forming part of the clamping ring 16. By the provision of this means it will be seen that the receiver may be quickly adapted to a given strength of received impulse by loosening the set screw 20 and by bodily rotating the cover 13 and horn 15 until a maximum sound emission is produced, after which the set screw 20 is tightened to lock the parts in adjusted position.

For the purpose of providing a stable loud speaking unit, my invention further includes a construction in which the parts are arranged to provide a structure having a low center of gravity. To accomplish this end the electromagnetic unit E is supported to be carried by a weighting magnet member 22 provided with the opposite poles 23 and 24 to which is attached the laminated L-shaped core pieces 25 and 26, the legs of the core pieces forming the cores for the electromagnetic coils 27 and 28 respectively, the feet of the core pieces being magnetically secured to the pole pieces 23 and 24, a non-magnetic clamping ring 29 in conjunction with the non-magnetic clamp pieces 30 and 31 being provided for clamping the core pieces to the magnet member 22, the screws 32 being provided for securing these parts together. The weighting magnet member 22 is designedly massive, and is positioned in a central opening 33 of the base B and is attached to the bottom 34 of the casing C as by means of securing screws 35 so as to be substantially housed by the said base, the mass and the position of this weighting magnet member producing a telephone receiving unit having the desired stability and low center of gravity.

For the purpose of providing a radio telephone receiver in which discordant vibrations of the electromagnetic unit E are minimized so as to permit of the obtaining of pure and clear tones, I provide means

for absorbing the vibrations of the electro-magnet elements, and in the preferred construction such means comprises a casing or enclosure 36 having a side wall and a bottom 5 wall which is preferably made of fiber, the said enclosure containing the coils 27 and 28, the space between the coils and the walls of the enclosure being filled with a vibration absorbing substance 37 such as wax.

10 For the purpose of preventing any abnormal stress on the diaphragm during adjustment of the same to obviate the possibility of injuring the same, I provide a construction in which motion of the diaphragm D 15 towards the electromagnet E is limited in a predetermined manner, the cover 13 and the casing body 12 being constructed to provide the stop or limiting means; and to this end the top marginal edge of the body 12 is 20 made substantially flush with the pole faces of the cores 25 and 26 and is adapted to engage the underneath wall of the cover 13 in the limiting position. By this means the diaphragm cannot be displaced or distorted.

25 to yield any abnormal stress therein, damage to the same being prevented. For connecting the electromagnet coils 27 and 28 to the output end of a receiving set, there is provided the spaced binding posts 38 and 39 30 carried by the base B and electrically connected to the coils by means of the conductors 40 and 41 respectively.

The method of making and using my improved radio telephone receiver will in the 35 main be apparent from the above detailed description thereof. It will be apparent that by the provision of the adjustably settable diaphragm D that quick and sensitive adjustment may be made in a simple manner 40 by the operator or user for compensating for different strengths of incoming signals or impulses and for adapting the telephone receiver to the characteristics of any particular radio receiving set. It will be further apparent that with my improved construction 45 a very stable, strong and durable unit is provided, with the parts inter-related to form a presentable and attractive receiving device.

50 While I have shown my device in the preferred form, it will be apparent that many changes and modifications may be made in the structure disclosed, without departing from the spirit of the invention, defined in the following claims.

I claim:

1. A telephone receiver comprising a casing, an electromagnetic means housed thereby, a cover for the casing, a diaphragm associated with said electromagnetic means, a ring clamping the diaphragm to the cover and having threaded engagement within the casing to vary the distance between the diaphragm and the said means, the said ring and casing being constructed to limit the

movement of the diaphragm towards the said means to prevent abnormal stress on the said diaphragm.

2. In a radio loud speaking receiver, a support, a weighting magnet member carried thereby and arranged thereon to provide a low center of gravity for the receiver, an electromagnet carried by said member, the said member providing magnet poles for the electromagnet, and a diaphragm associated with said electromagnet.

3. In a telephone receiver, an outer casing, electromagnet coil means, a diaphragm vibratable thereby, and provisions for dampening vibrations of said coil means comprising a non-magnetic inner casing containing said means and filled with a vibration absorbing substance.

4. In a telephone receiver, an electromagnet unit comprising an outer casing, spaced coils, L-shaped core pieces one for each coil, and a magnet member, the leg of each core piece forming the core of the magnet coil with the foot of each core piece attached to the said magnet member, and provisions for dampening vibrations of the said electromagnet unit comprising an enclosure containing said coils and filled with a vibration absorbing substance.

5. A telephone receiver or loud speaker comprising a base designed for horizontal support, a casing secured thereto, an approximately annular stabilizing magnet dependently secured to the casing and accommodated in an aperture in the base, said magnet having substantially opposite inwardly projecting pole members, and electro-magnet within the casing and having core members magnetically secured to said pole members and windings on upwardly projecting portions of the cores, a diaphragm supported adjacent the pole ends, a cap for the casing, and a horn mounted in the cap at an aperture therein.

6. A telephone receiver or loud speaker comprising a base designed for horizontal support, a casing secured thereto, an approximately annular stabilizing magnet dependently secured to the casing and accommodated in an aperture in the base, said magnet having substantially opposite inwardly projecting pole members, angularly formed magnet core members each having a portion magnetically secured to one of said pole members and an upwardly projecting portion, magnet coils about the pole members, a non-magnetic inner casing closely surrounding the magnet windings and filled with a vibration-damping material, a diaphragm supported adjacent the pole ends, a cap for the casing, and a horn mounted in the cap at an aperture therein.

7. A telephone receiver or loud speaker, comprising a substantially cylindrical casing, an electro-magnet therein, a ring having

screw threaded engagement in the casing to provide for adjustment in an axial direction by rotation of the ring, the ring having an inwardly projecting flange adjacent the casing wall, a set screw passing through a threaded hole in the casing wall and adapted to engage said flange to lock the ring in adjusted position, a cap secured to the ring for

turning the same to move the diaphragm ring and cap toward and from the electro-¹⁰ magnet, the cap having a central boss and a horn mounted therein.

Signed at New York city, in the county of New York and State of New York, this 24th day of August, A. D. 1922.

PAUL S. GRIERSON.
